UNITED STATES PATENT OFFICE

2,423,347

ARCHERY TARGET BUTT

Charles A. Saunders, Manilla, Iowa

Original application August 5, 1941, Serial No. 405,565. Divided and this application April 27, 1944, Serial No. 532,928

5 Claims. (Cl. 273—102)

1

This invention relates to improvements in archery target butts.

This application is a division of my prior application Serial No. 405,565, filed August 5, 1941, and entitled Method of making archery target butts and machinery therefor, now Patent Number 2,372,856, granted April 3, 1945.

Archery target butts hitherto have been made by hand without the assistance of special machinery. According to the method of the prior art, a handful of straw is twisted into a small spiral coil, from which the ends of the stalks protrude tangentially. The coil is stitched to hold it together. Thereafter the ends of another handful of straw are placed against the coil under the tangentially protruding portion, and both said protruding previous portion and the newly added straw are wrapped about the periphery of the coil, the ends of the preceding portion covering the beginning of the newly added portion. The free ends of the previously added portion are pulled tautly against the coil with one hand, and the body of said portion is hammered into place by means of a mallet wielded in the other hand. While still pulling on the free ends of the previously added portion with one hand, the body of said portion and the underlying ends of the newly added portion are fastened to the coil by means of a needle and twine manipulated with the other hand. Because of the resilient nature of the felted mat, it is necessary to fasten each handful of straw in position immediately after hammering it into place. The above described series of operations is repeated until a butt of the desired size has been made.

Not only is hand manufacture slow, tedious, and expensive, but in addition considerable difficulty is encountered in making the butt truly circular. Hand-made butts have the following principal defects: (1) They are not sufficiently dense, and accordingly wear out too rapidly under the pounding of the arrows. (2) The center region, where most of the arrows strike, is less tightly wound than the peripheral region, whereas it ought to be more tightly wound, since it is exposed to the greater wear. (3) The butt has a tapered rim, and arrows striking the thin portion thereof may pass completely therethrough and be stripped of their feathers or otherwise injured. (4) The striking surface is not sufficiently smooth and uniform. The target butts of the present invention do not have the above deficiencies.

In making my improved target butts, the straw or other raw material is coiled, compressed,

2

shaped, and continuously maintained in shape and under compression, by means of a taut, moving endless belt which substantially encircles the work while the article is being made. The straw is coiled about a mandrel (which however may consist of straw twisted into the necessary shape) rotated by the movement of the encircling belt. Suitable guides are provided to control the width of the butt, and to insure that the faces thereof are plane and relatively smooth.

The work is maintained in the desired shape and under suitable compression by the guides and the encircling belting throughout the course of manufacture, so that it is not necessary to interrupt the coiling operation to fasten down the work. After the work has attained the desired size, the otherwise complete butt may be sewed at one time while it is still in the machine. Or, if desired, a strip of fabric may be fed into the machine and thereby wrapped around the periphery of the butt. After the annular casing thus formed has been joined together in any suitable manner, the article may be removed from the machine and sewed at leisure, the annular casing meanwhile preventing expansion of the compacted mass comprising the article.

It is an object of the present invention, therefore, to provide an improved archery target butt.

Another object is to provide an archery target butt which has a relatively hard, densely packed midsection impermeable to arrows and relatively soft, smooth, uniform striking surfaces adapted to hold and retain a striking arrow.

Another object is to provide a spirally coiled butt which is more densely packed near the center than near the periphery.

The foregoing and such other objects, advantages and capabilities as may appear herein or be pointed out as this description proceeds, or as are inherent in the present invention, are illustrated in the accompanying drawings, in which:

Figure 1 is a central vertical longitudinal section.

Figure 2 is a plan view of a machine suitable for constructing the target butt of the present invention, the frame of said machine being shown in broken lines to avoid confusion.

Figure 3 is a fragmentary detail view in central vertical longitudinal section and illustrates the matforming portion of the machine shown in Figures 1 and 2 at the beginning of the cycle of operation.

Figure 4 is somewhat similar to Fig. 3, and illustrates a later stage in the manufacturing process.

Figure 5 is a vertical transverse sectional view taken on line 5—5 of Fig. 4.

Figure 6 is a fragmentary sectional view taken on a diameter of an archery target butt embodying the present invention, and illustrates the manner in which the center of the butt may be stuffed.

Figure 7 is a fragmentary elevational view of the periphery of my improved target butt.

Figure 8 is a front elevational view of the face of such a target butt.

Figure 9 is a fragmentary detail view in central vertical transverse section and illustrates a modified form of apparatus which dispenses with the use of a mandrel between the guide plates.

Like reference characters are used to designate similar parts in the drawings and in the description of the invention which follows.

Referring now more particularly to the drawings, Figures 1 and 2 illustrate one form of a machine suitable for making my improved archery target butts.

The machinery is arranged on a suitable framework 2 having legs 8, 8 and a shelf or table portion 3. Movably arranged upon the framework 2 near one end thereof is a belt tightener, exemplified by the sliding carriage 4 mounted upon the rails 37, 37 and carrying the pulley 6. Near the opposite end of the frame 2 the mandrel 7 is positioned. The framework supports a superstructure or scaffold 9. Upon this scaffold is suitable means for driving a belt, exemplified by the electric motor 10. Attached to said motor 10 is the drive wheel 11. Passing over the pulley 6, the mandrel 7, and the drive wheel 11 is the endless belt 12.

To the belt tightener is attached a suitable tensioning device, exemplified by the weight 13 which is attached to the carriage 4 by means of the cord 14, which passes over the pulley 15. Alternatively, one end of a spring may be attached to the carriage 4 and the other end may be attached to some fixed portion of the framework 2 whereby motion of the carriage to the observer's right is yieldably resisted. Or, if desired, the pulley 6 may be fixed, and the necessary tension may be obtained by making the belt 12 of elastic material and stretching it tautly between said pulley 6 and the mandrel 7.

If desired, an idler pulley 16 may be placed near the drive wheel 11 so as to guide the belt 12 to avoid slipping between the belt 12 and the drive wheel 11.

The ledge 3 is inclined somewhat to the right. To it is joined the mouth of the hopper or feeding guide 17. The discharge end of said hopper empties upon the belt 12 slightly in front of the mandrel 7. Said mandrel is supported by the idler 18 which is carried by a movable carriage 19 which moves along the ways 20, 20 forming an extension of the framework 2. Said carriage may be manually slidable or, if desired, it may be attached to a worm 21, operated by the synchronous motor drive 22. In the latter arrangement, the motor 22 moves the idler carriage 19 and the pulley 18 thereon progressively to the right.

Mounted upon the scaffold 9 is the pivotal guide arm 23. The said guide arm 23 is slotted, and the brace 30 passes through said slot and limits the movement of said guide arm 23 to a vertical plane. Attached to the free end of said guide arm 23 is the guide roller 25, which rests upon the belt 12. Projecting from the scaffold 9 is the fixed guide arm 26, which likewise carries

a guide roll 27 under which the belt 12 passes.

Fixed to the mandrel 7, on each side of the belt 12, are the circular guide plates 28, 29. Said guide plates 28 are spaced by the mandrel 7, and said plates and said mandrel are mounted concentrically on the center stud 29 (see Figure 5).

Fig. 9 illustrates a modification of the apparatus, in which the frame 2 is provided with brackets 38. The upper surface of each of said brackets 38 follows the arc defined by the center of the butt as the work increases in size. The mandrel 7 and the center stud 29 are dispensed with, and the straw or the like is coiled about a plug formed of the same material. If desired, the end guides 40, 40 may be provided with points 41, 41 to be anchored in said plug 39. Protruding outwardly from the center of each guide plate 40 is a bearing 42, which, if desired, may be flanged as shown. One or more spacer clamps 43 may be employed to prevent the guide plates 40, 40 from becoming separated too far while the butt is under construction.

For purposes of illustration, I shall now describe the construction of a straw archery target butt with the aid of the foregoing apparatus. It is distinctly to be understood, however, that my improved archery target butts may be made of fibrous materials other than straw such as vegetable fibers for example.

At the beginning of the cycle of operation, the machine is in the condition illustrated in Figures 1, 2, and 3, the pulley carriage 4 being in its extreme position to the left. The mandrel 7 floats upon the idler 18. The guide plates 28, 28 are rotatably attached to the mandrel. The subassembly consisting of the mandrel, center stud, and guide plates is held in place by the guide arm 26, the end of which projects between the two guide plates 28. The idler pulley 27 at the end of the guide arm 26 rests upon the belt 12 and causes said belt almost completely to surround the mandrel 7. The pivotal guide arm 23 is supported suitably, so that the roller 25 is maintained a few inches above the belt 12. A supply of straw 31 is placed upon the table 3. The motor 10 moves the belt 12 in the direction indicated by the arrows. An operator manually feeds the straw 31 into the hopper or feed funnel 17. If desired, the straw may be twisted into a rope before being fed into the hopper 17, or while being so fed.

The straw 31 passes through the hopper and is fed upon the belt 12 through the discharge end of said hopper, said discharge end being adjacent the guide pulley 27. The motion of the belt feeds the straw 31 between the mandrel 7 and the belt 12. When the machine begins to operate, the mandrel 7 is rotated by frictional engagement with the moving belt 12. As more straw 31 is fed into the machine, it is wrapped spirally about the mandrel 7. At this stage, the mandrel and the work rotate, but the guide plates 28, 28 usually do not.

As the work becomes larger, frictional engagement of the coiled straw with the guide plates causes the latter to rotate with the work and the mandrel. Also, the work will raise the belt 12 until it makes contact with the roller 25 and floats the pivotal guide arm 23 off its support. Thereafter said roller 25 will rest upon the work and assist in compressing the same. If desired, said guide arm 23 may be suitably loaded, as shown at 44, to increase the pressure upon the work. The guide arm 23 maintains the guide

plates 28, 28 in vertical position, and prevents said guide plates from wobbling.

The weight 13 keeps the belt 12 under tension at all times. As the work progresses, the parts take the relative positions shown in Figure 4. It is to be noted that the belt 12 almost completely surrounds the work 32 throughout the course of operation, and that the tension of the belt serves to compress the work at all times. This is necessary because a resilient material like straw would spring out into a relatively porous mass if the tension were removed.

The tension upon the belt exerts a force against the work in the form. At the beginning of the operation the total force is distributed over the relatively small peripheral area of the work, for which reason the pressure (force per unit area) is greatest when the size of the object is smallest. As the coiling operation proceeds and the unfinished butt becomes larger, the total force due to the belt tension is distributed over a larger peripheral area, and the pressure, therefore, is less. Thus the pressure upon the work is automatically varied so as to construct an improved article which is densely packed near the center, and in which the density of felting progressively increases from the periphery to the center.

As the butt increases in size, the quantity of belt in peripheral contact therewith likewise increases. This causes the carriage 4 to be drawn to the right and the weight 13 to be lifted.

The work is supported by the idler 18. As the coiling proceeds, the mandrel 7 will be displaced upwardly and to the right. Since the center of gravity of the work follows the mandrel 7, it is desirable to move the idler 18 to the right also, as the work progresses. This may be done in any convenient way, as for example by mounting the idler carriage 19 upon a screw 21, so that said carriage may be translated by rotation of said screw. Preferably, said screw is revolved by a synchronous electric motor 22 at such a rate that the idler 18 moves to the right somewhat more rapidly than the mandrel 7. This causes the work to be cradled between the guide roller 27 and the idler 18, as shown in Figure 1 in dotted lines. This arrangement is effective in preventing rocking of the work, as might be the case if it were supported only by the idler. Further, this arrangement increases the clearance between the bottom of the belt 12 and the roller 27, making it possible to increase the rate at which straw is fed to the work as the latter increases in size.

I prefer to use a crowned idler 18 having a peripheral width somewhat less than the space between the guide plates 28, 28. The weight of the work tends to crush the straw against the idler, and the arrangement above mentioned results in the formation of an article having a midsection more densely packed than the surface layers. The relatively loose surface layers are easily penetrated by arrows, so that arrow rebounds are minimized; whereas the densely packed central layer prevents the arrows from passing therethrough. This effect can be heightened by feeding the straw to the center of the belt, which is readily effected by appropriate adjustment of the discharge end of the hopper 17.

The pressure upon the work crushes the straw 31 against the guide plates 28, 28, with the result that the striking surfaces of the butt are planar, smooth, and uniform. This improves the appearance of the article, and causes the faces

to remain usable for longer periods of time than has heretofore been possible.

The coiling operation may be continued until the butt has been built up to any desired size. At the end of this operation, the pulley carriage will be in the position shown in Figure 1 at 4', the pivotal guide arm will be in the position shown at 23', the idler support carriage will be in the position shown at 19', the guide plates will be in the position shown at 28', and the work will have the size and position indicated at 32'. The motors 10 and 22 are then stopped. One or both of the guide plates 28, 28 may be removed, and the butt may be sewed while it is in the machine, in order to maintain the article in compressed condition. Alternatively, the guide plates 28 may be perforated in such manner as to permit the butt to be sewed without removing said plates.

After the sewing operation has been completed, the tension on the belt is relieved, as for example, by disconnecting the weight 13 from the pulley carriage 4. Then the guide plates 28, 28 are removed, and the mandrel 7 and butt are removed from the machine. The center stud 29 is knocked out, the mandrel 7 is filled with a portion of tightly twisted straw 34, and thereafter the mandrel is knocked out of the butt, care being taken to drive the straw out of the mandrel into the space being vacated by the mandrel itself. As the mandrel 7 is withdrawn from the butt 32, more straw is stuffed into the hollow space left by the mandrel, in order to provide a solid butt having a tightly packed center.

Figure 9 illustrates an alternative arrangement for fabricating a butt built around an initial solid center. A small quantity of straw is twisted or compacted into a plug 39 which serves in place of the mandrel. This plug or small coil may be suitably fastened together, as by stitching, if desired. Said plug 39 is encircled by the belt 12, and the guide plates 40, 40 are pinned to it as shown, the points 41, 41 being inserted in the ends of the plug along the axis thereof. Each guide plate 40 is supported upon a bracket 38 by means of a bearing 42. Said bearings 42, 42 may be flanged as shown to engage the bracket sides and prevent wobbling of the guides 40, 40. One or more spacer clamps 43 may be employed to prevent the peripheral edges of the guides 40, 40 from separating too far from each other. It will be understood that said clamps 43 do not rotate with said guides 40, 40. As the work grows larger, the bearings 42, 42 will move along the brackets 38, 38, following substantially the same trajectory as the mandrel 7 does in the previously discussed embodiment. In other respects, the construction of the butt is the same under both arrangements, except, of course, that in the arrangement shown in Figure 9, it is not necessary to remove any mandrel and stuff the hollow space left thereby.

Figure 7 is a fragmentary central section along a diameter of the finished butt, and shows the stitching 35, the stuffed core 34, and the flat peripheral edge 36. My improved target butt has a relatively constant diameter rim, which is much to be preferred over the rounded peripheral edge of the target butts of the prior art, because arrows which strike near the periphery of my improved butt will be caught, instead of passing through a thin edge region and thereby being stripped of their feathers.

Instead of stitching the butt while it is under compression in the machine, the following alternative procedure (which is the preferred pro-

cedure) may be followed. When the butt has reached the desired size, a strip of burlap, heavy wrapping paper, or other suitable fabric is fed into the hopper 17, whereupon the movement of the belt 12 causes said strip to be wound around the periphery of the butt 32. Thereafter, the ends of the fabric are joined together in any suitable manner, as for example, by means of buckles. Or the fabric may be passed several times around the butt and the overlapping layers may be sewed together. Thus the coiled straw disk is prevented from uncoiling by the fabric belt in which it is retained. The straw disk and its surrounding belt may now be removed from the machine. The article may be sewed in the usual manner at any time thereafter. It will then present the appearance shown in Figure 8, in which the fabric casing is designated at 45, and the stitching at 35. If desired, the casing 45 may be removed after the straw has been sewed down, but I prefer to sew said casing 45 to the rest of the butt in order to utilize it as a permanent reinforcement.

Comparison between target butts embodying the present invention and ordinary target butts, conclusively demonstrates the superiority of the former. My target butt is round, has planar, parallel, and smooth striking faces, and a cylindrically shaped rim. The straw or other fiber is packed together far more compactly than is the case in prior constructions. Because of this, one of my improved target butts of tournament quality and having the standard diameter and weight is substantially thinner than the previously known target butts, and therefore is more convenient to handle, and takes up less storage space. Because the density of packing is greatest where the wear is greatest, my improved targets are particularly long wearing.

While I have explained how my improved archery target butt may be made by utilizing the apparatus described and claimed in my copending application Serial No. 405,565, it will be apparent to those skilled in the art that my new article may be made by any method utilizing the principles hereinabove set forth.

Having thus described my invention and illustrated its utility, I claim:

1. An archery target butt comprising a disk of compressed straw, a belt encircling the same, and stitching binding said butt into a unitary whole; a relatively non-tapered rim on said disk substantially perpendicular to the striking surfaces thereof, the straw on said striking surfaces being crushed relatively flat and smooth; said disk comprising a tightly compacted central straw core having the strands thereof twisted helically about the axis of said disk, and straw twisted into rope-like lengths and coiled spirally about said central core, the density of packing of said spirally coiled straw increasing regularly from the periphery of said disk to the central region thereof, and also increasing from the striking surfaces to the mid-section thereof.

2. An archery target butt consisting of a disk

of compacted fibrous material, a belt encircling the same, and thread material binding said butt into a unitary whole; smoothed faces on said disk, and a relatively non-tapered rim thereon substantially perpendicular to said faces; said disk comprising a compacted cylindrical core portion of fibrous material substantially parallel to the axis of said disk, and fibrous strands twisted into rope-like lengths and coiled spirally about said core portion, the density of packing of said spirally coiled fibrous strands continually increasing from the periphery of said disk to the central region thereof, and also increasing from the striking surfaces to the midsection thereof.

3. An archery target butt comprising a disk of compacted fibrous material, a casing encircling the rim of said disk and maintaining the material thereof under compression, and thread material sewing said butt together; smoothed faces on said disk, and a relatively non-tapered rim thereon; said disk comprising a central fibrous core the fibers of which are twisted helically about the axis of said disk, and fibrous strands coiled about said central core, the density of packing of said coiled fibrous strands increasing regularly and continually from the periphery of said disk to the central region thereof.

4. An archery target butt comprising a cylindrical central portion of fibrous material wherein the ends of said fibrous material are generally presented to the striking arrows, fibrous strands twisted into rope-like lengths and coiled spirally about said central portion, said fibrous strands being coiled progressively less tightly outwardly from said central portion, a belt tautly encircling said fibrous material, and thread material sewn through said fibrous material and binding the same into a compact disk, said disk having smoothed faces and a relatively constant diameter rim substantially perpendicular to said faces.

5. An archery butt, including: a substantially cylindrical inner portion comprising fibers twisted together about the axis of said inner portion, whereby the ends of said fibers are generally presented to the striking arrows; and an annularly shaped outer portion surrounding said inner portion and having a substantially cylindrical outer rim, said outer portion comprising fibrous strands twisted into rope-like lengths and spirally wound about said inner portion, the density of packing of said fibrous strands increasing regularly and continually from the periphery of said outer portion to the central region thereof.
